UNITED STATES PATENT OFFICE.

MATHEW HILGERT, OF NEW YORK, N. Y.

LAST.

1,120,490.

Specification of Letters Patent.

Patented Dec. 8, 1914.

Application filed June 8, 1914. Serial No. 843,726.

To all whom it may concern:

Be it known that I, MATHEW HILGERT, a citizen of the United States, and resident of the borough of Manhattan, city, county, and 5 State of New York, have invented certain Improvements in Lasts, of which the following description, in connection with the accompanying drawings, is a specification, like reference characters on the drawings indicating like parts in the several figures.

10 This invention relates to lasts.

More especially it relates to lasts adapted for use in the process of making shoes set forth in an application filed by me 15 currently herewith.

In practising this process, a last of unusual construction is required on which to make the shoe, as will be explained more fully hereinafter, and it is the primary 20 object of the present invention to produce the required last.

Referring now to the accompanying drawings, Figure 1 is a plan view of a form which preferably is used in practising this 25 process; Fig. 2 is an angular view showing the bottom of the form illustrated in Fig. 1; Fig. 3 is an angular view similar to Fig. 2 but showing a filler secured on the bottom of the form; Fig. 4 is an angular 30 view of the filler illustrated in Fig. 3, but showing the filler in an incomplete state; Fig. 5 is an angular view of the bottom of the filler shown in Fig. 4; and Fig. 6 is a view in side elevation of the required last.

35 In making the required last, it is first necessary to make a model from which to make the last. I prefer to make this model by first making a foot-shaped form or last similar to an ordinary last but having its bottom 40 face shaped to conform to the more prominent projections and depressions of the foot. Such a form is shown at 2 in Figs. 1 and 2 of the drawings, from which it will be seen that the form has substantially the 45 lateral, instep and upper surfaces of a last made for a substantially normal foot, but the bottom face includes a well rounded heel 4, an arch surface 6 deeper than that usual in the ordinary last but substantially 50 like that of a normal foot, and a forepart surface nearly flat but with a slightly rounded portion or protuberance at 8 corresponding to the joint of the great toe. The extent to which the detailed duplication of 55 the features of the bottom of the foot are carried out can be varied as circumstances

require; but ordinarily, in making a form of a given size, only the more prominent features of the foot, which will not vary to any great degree in the majority of feet of 60 the same size, will be reproduced in the form. This form, therefore, is made of the dimensions and shape required to construct a shoe for a substantially normal foot of a given size, but differs from the usual last 65 of the same size and style in its bottom contour. The form 2 having been completed, I next make a filler 10. This filler or a substantial duplicate of it later will be used in the shoe to be made on the last produced 70 by this process. The filler 10 is made to fit the bottom of the form 2 and is shown in Figs. 4 and 5 in an incomplete state for the purpose of illustrating more clearly its construction. A number of methods of making 75 this filler will suggest themselves to those skilled in this art, but one very satisfactory method consists in dieing out a piece of leather 12 of the shape required to fit the bottom of the form 2, tempering it and then 80 securing it to the form with tacks until it has dried to the shape of the form. A rand 14 is then glued around the heel part of the leather piece 12 and a piece 16 of felt or similar material is glued to the forepart, 85 this felt being first given the desired shape, as for instance by running it through a splitting machine equipped with a suitably shaped die roll or by using a suitable templet in connection with the splitting machine, as will be readily understood by those 90 familiar with such machines. According to this method, the filler is made on the bottom of the form and the parts 14 and 16 are shaped to give to the upper surface of the 95 filler a contour conforming to that of the bottom of the form, which contour will be retained after the filler is removed from the form. The lower surface of the filler may be given any desired shape, but preferably 100 is shaped like the bottom of an ordinary last. If the lower surface of the filler is rough or uneven it should be scoured or treated in a similar manner to level it up. Inasmuch as most feet have a slight "out- 105 side roll" or a tendency to bear too heavily on the outer edge of the foot, I prefer to make the outer edge of the filler 10 of greater average thickness than the inner edge in order to compensate for or correct 110 this tendency. This result is accomplished in the filler shown by shaping the felt mem-

ber 16, as shown in Fig. 5, so that it is somewhat thicker on the outside portion where the joint of the little toe will bear on it than on the inside under the great toe joint. The top and bottom surfaces of the filler are next covered with some suitable material such as cloth or leather.

When the finished filler 10 is secured in its normal or operative position on the bottom of the form 2, these parts together constitute the model from which to turn the required last; but inasmuch as the filler, while having a substantially permanent shape, is made of material that might yield sufficiently under the pressure of the model wheel of the last turning lathe to prevent the lathe from making an exact reproduction of the model, I prefer to reinforce the filler. This may conveniently be done by soaking the filler in some hot liquid composition that becomes firm and solid when cooled to ordinary temperatures. I find that a very satisfactory composition for this purpose can be obtained by mixing 8 1/4 per cent. of Malayan gum with 12 1/2 per cent. of ozokerite and 6 1/4 per cent. of Montan wax. This composition may be easily melted and the filler, when soaked in it and allowed to cool, will be found to be practically as firm as a piece of wood. This method of reinforcing the filler has the further advantage that it does not change the dimensions of the filler and, consequently, does not modify the form or dimensions of the model. The filler made for the purpose of making the model from which to turn the last may, if desired, be made of materials other than those specified such for instance as leather or fiber or some material that is sufficiently firm and unyielding to require no reinforcement, but still can be given the required shape. The model is now complete, consisting of the form 2 and the filler 10 secured thereto, the filler, if made of yielding material, preferably being reinforced as above described. The required last can now be obtained from this model with the aid of the usual last making machinery simply by following the well-known method of making a last from a model. The last produced in the manner

just described is indicated at 18, Fig. 6. With this last, an orthopedic shoe can be made in exactly the same way that a standard or ready-made shoe is manufactured in shoe factories, and when the shoe is completed, by inserting in it the filler 10 or a duplicate thereof, it will then fit the foot for which the form 2 was originally made with an accuracy impossible with ordinary ready-made shoes. It has been considered possible heretofore to make such shoes only by hand; but by first making a last according to the process above described, such shoes can then be made by modern shoe making machinery and at only a slightly greater cost than that of manufacturing a standard shoe of the same quality.

It is obvious that a metal last can be made from the model above described in the usual manner.

The novel process of making shoes described herein is claimed in my application Ser. No. 843,727, filed June 8, 1914, and is not claimed in the present application. The novel process of making the last described herein is claimed in my application Ser. No. 856,423, filed Aug. 12, 1914, and is not claimed herein.

Having thus described my invention, what I claim as new and desire to secure by Letters Patent of the United States is:

As a new article of manufacture, a last so made as to correspond in shape and dimensions with a last made for the foot with its bottom face shaped to conform to the bottom of the foot plus a filler having one face shaped to conform to the bottom of the latter last and the other face shaped like the bottom of an ordinary last, the bottom of the former last being sufficiently rigid to withstand the pressure of the usual leveling and heeling machines.

In testimony whereof I have signed my name to this specification in the presence of two subscribing witnesses.

MATHEW HILGERT.
